UNITED STATES PATENT OFFICE.

GUSTAVE E. FRANQUIST, OF NEW YORK, N. Y., ASSIGNOR TO J. B. COLT COMPANY, A CORPORATION OF NEW JERSEY.

FEEDING MECHANISM FOR ACETYLENE-GAS GENERATORS.

SPECIFICATION forming part of Letters Patent No. 746,812, dated December 15, 1903.

Application filed December 12, 1901. Serial No. 85,697. (No model.)

To all whom it may concern:

Be it known that I, GUSTAVE E. FRANQUIST, a resident of the borough of Manhattan, in the city and State of New York, (post-office address No. 21 Barclay street, in said borough,) have invented certain new and useful Improvements in Feeding Mechanism for Acetylene-Gas Generators, of which the following is a description, accompanied by drawings.

The invention is particularly designed and adapted for use in the feeding of carbid in acetylene-generators.

In many carbid-feeding mechanisms, and particularly in the various forms of gravity-feeds, a valve or stop is used for preventing the feeding of carbid. It sometimes occurs that a particle of carbid will prevent the tight closing of the valve or stop and allow leakage or feeding of the carbid. To obviate this trouble, auxiliary valves or safety-stops have been resorted to.

It is the object of the present invention to produce a valve of simple construction which shall be free from all serious danger of such interference or leakage of the carbid.

In the preferred form of the invention a series of separate fingers or stops are used, so that the interference or holding up of one of these will not prevent the proper closing movement of the others, and in conjunction with such fingers or stops a valve, preferably with a rubber edge, so as to be substantially gas-tight and moisture-proof, may be employed. Preferably, also, such valve will close after the series of fingers or stops and will operate at a point beneath the fingers or stops and will come into operation, therefore, when the valve-seat is practically free from carbid. Such valve therefore will only have to operate upon such small quantity of carbid as may pass the series of stops. This construction of feeding mechanism is especially well suited to the feeding of granular carbid.

In the drawings, Figure 1 is a vertical central section of one form of the feeding mechanism as applied to the carbid-hopper of an acetylene-generator. Fig. 2 is a plan view of the uppermost parts of the carbid-hopper, showing the protruding end of the rock-shaft

which operates the feeding mechanism. Fig. 3 is a cross-section of certain details of the feeding mechanism on the plane 3 3 of Fig. 1. Fig. 4 is a partial vertical section of a modification. Fig. 5 is a horizontal section of the same on the plane 5 5 of Fig. 4.

In Figs. 1, 2, and 3, *b* is the carbid holder or hopper, shown in this instance as having a tapering lower end, *c* a casting which contains the bearings for the rock-shaft *f* of the operating-lever *g*, and *d* is the carbid-charging cover held in place by a movable yoke *h* and hand-screw *j*. The valve mechanism is protected inside of the hopper from the carbid by the housing *k k' k''*. The inner valve or stop *l*, preferably leading to the generating-chamber, has a rubber flange or edge for making a tight moisture-proof contact with the valve-seat, as seen in the figure, and is mounted upon and operated by a rod *m*, connected by a link *p* to the inner arm *g* of the operating-lever. The details of the operating connection may be varied at will, as they are not essentials of the invention. Means are provided carried by the valve to be elevated by the valve in its upward movement and to lower with said valve in its downward movement for a portion of said downward movement, said means being adapted to engage the tapering sides of the chamber before the valve engages its seat and to cut off the supply of carbid above the valve. As shown, in this instance the rod *m* may be guided in the two heads *r*, which should also serve as guides for the series of fingers or stops *s*. Attached to the rod *m* is a pick-up head *t*. Each of the stops *s* is provided with an engaging member *u*, which is engaged and lifted by the head *t* and forms the means by which the respective stop *s* is raised. I have shown the members *u* as being placed at different heights on the different stops, so that as the head *t* rises some of the stops will be raised in advance of the others. This is advantageous for the feeding of granular carbid, because the raising of one of the stops in advance of the others allows a more gentle feeding of the carbid than if all were raised at once. From the operation the proportioning of the parts under different conditions will be clear to those skilled in the art.

The operation of the device is as follows: When the rod *m* is raised to feed, it first raises the valve or stop *l* without raising any of the stops *s*. As the stops *s* remain seated on the 5 surface of the hopper, the raising of the valve *l* will not in itself allow any carbide to be fed unless some has leaked through the fingers or stops *s* and settled above the valve *l*. If the rod *m* is now raised farther, the head *t* 10 engages and raises one or more of the members *u*, and with them the corresponding stops or fingers *s*, permitting the carbide to fall down the inclined surface of the hopper and through the feed-opening of the hopper beneath the 15 valve *l*. When the feeding is to cease, the rod *m* is lowered, allowing all the stops *s* to descend until they come to rest against the hopper. When these conditions are reached, the interval within the series of stops 20 *s* will become free from carbide unless some carbide leaks through between the fingers or stops *s*. When, therefore, the further descent of the rod *m* closes the valve *l*, either this valve will have no carbide to interfere with 25 its seating itself or it will only have to contend with such fine carbide in such a small quantity as may continue to leak through the stops *s*. The valve *l* may be employed for both its functions of excluding moisture 30 from the carbide and of stopping the fine carbide that passes the stops *s*. It may under proper conditions be constructed and employed to serve only one of these two functions. For example, when coarse granular 35 carbide is used with very little carbide-dust the stops *s* may be sufficient to entirely prevent the feeding of the carbide.

In the modification shown in Figs. 4 and 5 flat plates *s'* are shown in the place of round 40 fingers or stops *s* and the engaging members *u'* take the form of studs or lugs on the stops *s'*, which are engaged by the cylindrical weight *t'* on the central rod *m*. These are the principal differences in the form of the 45 device shown in Figs. 4 and 5 from that shown in Figs. 1, 2, and 3.

It will thus be seen that according to my invention there is provided a generating or slaking chamber, a portion only of which is 50 indicated in the drawings, and a carbide-holder having an exit-opening in communication therewith, and there are a plurality of independently-movable valves, one placed in the rear of and surrounding the other, both of 55 said valves being adapted to coact with the wall of the said exit-opening for closing it, while means are provided, constructed, and arranged to close the rear valve in advance of the foremost valve.

60 I do not limit the use of the term "movable stops" to the separate fingers *s*, as I also term the valve *l* a "stop."

I claim and desire to secure the following characteristic features:

65 1. In combination with a feed mechanism, a carbide-holder having an exit-opening for

the material to be fed, a plurality of movable stops for controlling said passage-way, one of said stops surrounding the other and means for actuating said stops to control the feeding, whereby one of them is operated in advance of another for substantially the purposes set forth. 70

2. In combination with a feed mechanism, a carbide-holder having an exit-opening for 75 the material to be fed, a plurality of movable stops for controlling said passage-way, one of said stops surrounding the other and means for actuating said stops to control the feeding while leaving them free to act independently within limits for substantially the purposes set forth. 80

3. In combination in a feed mechanism, a passage-way for the material to be fed, a plurality of movable stops for controlling the 85 feeding of material through said passage-way and another stop or valve for the said passage-way, and means for operating all the said stops and closing the last said stop or valve the latest, for substantially the purposes set forth. 90

4. In combination with a feed mechanism, a passage-way for the material to be fed, a plurality of movable stops for controlling said 95 passage-way, means for operating the stops, and a housing independent of the stops in which they are guided for substantially the purposes set forth.

5. The combination of the feed-hopper having an inclined bottom and a feed-opening, 100 a valve or stop for substantially closing said opening, a series of movable stops which rest when closed upon the said inclined bottom at a point above the first said valve or stop, and means for operating the said valve or stop 105 and the said movable stops, for substantially the purposes set forth.

6. The combination of the feed-hopper having an inclined bottom and a feed-opening, 110 a valve or stop for substantially closing said opening, a series of movable stops which rest when closed upon the said inclined bottom at a point above the first said valve or stop, means for operating the said valve or stop, 115 and lost-motion connections for raising the movable stops later than the first said valve or stop, for substantially the purposes set forth.

7. In a generator, the combination of a duplex feeding-valve for controlling the generation of gases, consisting of at least two relatively movable members and means for actuating them to open and close the valve, 120 whereby one of the members closes first and opens last, for substantially the purposes set forth.

8. In a generator, the combination of a duplex feeding-valve for controlling the generation of gases, consisting of at least two relatively movable members and means for actuating them to open and close the valve, 125 whereby one of the members closes first and opens last, and a housing for guiding and 130

protecting both of said members from the loose material for substantially the purposes set forth.

9. In an acetylene-gas generator, the combination with a generating-chamber, of a carbid-holder communicating therewith and provided with a tapering lower end, a valve-seat, a valve adapted to engage said seat, means carried by the valve to be elevated by said valve in the upward movement of the valve and to lower with said valve in its downward movement for a portion of said downward movement, said means adapted to engage tapering sides of the chamber before the valve engages its seat and to cut off the supply of carbid above the valve, substantially as set forth.
10. In an acetylene-gas apparatus comprising a slaking-chamber, a carbid-holder having an exit-opening in communication therewith, a plurality of independently-movable

valves, one placed in rear of and surrounding the other, both said valves adapted to contact with the wall of said opening for closing it, and means constructed and arranged to close the rear valve in advance of the foremost valve, substantially as described.

11. In combination with a feed mechanism, a passage-way for the material to be fed, a plurality of movable stops for controlling said passage-way, means for operating the stops, and a housing in which they are guided, the stops being movable relatively to the housing, for substantially the purposes set forth.

Signed this 4th day of December, 1901, at New York.
